(57) **CLAIM**

The ornamental design for an organizing grid for storage case, as shown and described.

DESCRIPTION

FIG. 1 is a left, front, top perspective view of the organizing grid for storage case;

FIG. 2 is a front elevation view thereof;

FIG. 3 is a back elevation view thereof;

FIG. 4 is a left elevation view thereof;

FIG. 5 is a right elevation view thereof;

FIG. 6 is a top view thereof; and,

FIG. 7 is a bottom view thereof.

The shade lines in the Figures show contour and not surface ornamentation.

The evenly spaced broken lines and the unshaded areas within them show portions of the organizing grid for storage case that forms no part of the claimed design.
